FILLING JIG FOR CARTONS

Clyde H. Troust, Buffalo, N. Y., assignor to F. N. Burt Company, Inc., Buffalo, N. Y., a corporation of Delaware

Application October 18, 1950, Serial No. 190,689

8 Claims. (Cl. 226—129)

1

This invention relates to improvements in a supporting device for supporting paper and like cartons during the filling thereof with merchandise, and more particularly to an improved filling and supporting jig for supporting paper and like cartons of relatively large sizes for storage or shipment and holding them to shape and size during the packing of the merchandise therein such as ice cream or other frozen foods. While the improved supporting jig may be used with various sizes of cartons, it has been designed for use with larger sizes such as capacities of 2, 3, or 4 gallons or larger.

It is a general object of the invention to provide an improved supporting jig for use in supporting paper or like cartons to prevent outward bulging, distortion, or rupture of the carton walls during packing of the contents firmly in the carton, and for retaining the carton to exact volumetric capacity during the filling, and being constructed and arranged so that it can be quickly and easily applied in supporting position before the filling of the carton and quickly and easily removed after the filling has been completed.

A further object of the invention is to provide a supporting jig of the class mentioned for use in filling cartons and having an improved sectional wall construction in which the sections are releasably hinged together to facilitate placing it in position on the carton and removing it therefrom, and having strong supporting walls preferably of sheet metal or like sheet material and having an improved attaching means to attach the sections together and at the same time exerting pressure against the outer surface of the carton walls to conform them to the desired carton capacity and to support them firmly in such position during the packing of the contents in the carton.

According to a feature of improvement of the illustrative embodiment of the invention, the supporting jig is made in two supporting sections hinged together at adjacent edges, and having an improved cam latch at opposite section edges having cam elements interengaging to urge the sections of the supporting jig into final supporting position and to hold them in such position during the packing of the contents in the carton.

A further object of the invention is to provide a supporting filling jig of the class mentioned provided with an improved attaching hinge and with an improved cam latch for the sections of the jig constructed and arranged to present a

2

smooth and unobstructed inner wall surface which contacts with the carton walls, and having an improved arrangement whereby the parts of the hinge and cam latch can be quickly engaged and disengaged, and having no partially closed areas or cavities for accumulations of dirt or bacteria whereby it can easily be cleaned.

Another object of the invention is to provide in a supporting filling jig of the class mentioned, an improved arrangement whereby the sections of the jig can be quickly and easily detached from each other and nested together so as to require little space for housing or storage thereof.

15 Other objects of the invention will be in part pointed out in the following detailed disclosure of an illustrative but preferred embodiment of the invention, and will be in part obvious as the disclosure proceeds.

20 The invention accordingly comprises the features of construction, combination of elements, and arrangement of parts, which will be exemplified in the construction hereinafter set forth and the scope of the application of which will be indicated in the claims.

25 For a more complete disclosure of the nature, objects and advantages of the invention, reference is had to the following detailed description of the illustrative embodiment, and to the accompanying drawings in which:

Fig. 1 is a top perspective view showing a paper carton filled with ice cream or similar material and having the improved supporting jig applied thereto in supporting relation;

35 Fig. 2 is a perspective view similar to that of Fig. 1 but showing the carton and jig viewed from the opposite side thereof;

Fig. 3 is a top plan view, parts being shown in horizontal section, of the supporting jig showing 40 in full lines the sections thereof connected together in operative position, and showing in broken lines the sections disconnected along one edge thereof and separated in position for applying or removing it from the carton;

45 Fig. 4 is a fragmentary enlarged detail elevation of the improved detachable hinge connection, parts being in section;

Fig. 5 is a cross section substantially on the 50 line 5—5 of Fig. 4 looking in the direction of the arrows;

Fig. 6 is a cross section taken substantially on the line 6—6 of Fig. 4 looking in the direction of the arrows;

55 Fig. 7 is a fragmentary elevation showing in

engaged position the cam connection or latch for connecting the sections together;

Fig. 8 is a view similar to Fig. 7 but showing the elements of the cam disconnected; and

Fig. 9 is a partially diagrammatic horizontal sectional view showing the method of nesting the two sections of the jig together for storage, etc.

Referring to the drawing for a detailed description of the illustrative embodiment of the invention, the filling and supporting jig is constructed for use with cartons that are square in horizontal section, such as paper carton 10, but it will be understood that it may be constructed for use with other shapes of cartons such, for example, as those that are polygonal in cross section with any desired number of sides, or even those that are cylindrical or oval. The supporting jig is made in two integral sections 11 and 12, the section 11 having two wall plates 13 and 14 positioned at right angles to each other, and the section 12 having two wall plates 15 and 16 also disposed at right angles to each other. Thus one of the wall sections is adapted to contact with one of the outer faces of the carton walls, being substantially the same dimension horizontally as the corresponding carton wall. But the vertical dimension of each wall plate is preferably somewhat less than the vertical height of the carton so that the carton wall projects slightly above the upper edge of the supporting jig when the latter is in supporting position as shown in Figs. 1 and 2. Each of the sections 11 and 12 is preferably made of strong sheet material such, for example, as metal, stainless steel being preferred.

Connections are provided between the two sections 11 and 12 at adjacent edge portions thereof as shown whereby, when the two sections are connected together in operative position, they completely enclose and support the carton being filled. It will thus be seen that the connections between the two sections are positioned at diagonally opposite corners of the supporting jig.

One of the connections is in the form of a detachable hinge between the two sections 11 and 12 as shown in detail in Figs. 3, 4, 5 and 6. This hinge connection includes a diagonally disposed outwardly turned upper flange 17 on one section and a similarly positioned outwardly turned lower flange 18 on the other section. Each flange 17 and 18 is provided near its base with an elongated vertically disposed aperture 19 for receiving another part of the hinge disposed upon the adjacent section. This detachable hinge also includes short flanges or hinge lugs 20 and 21 on the respective sections 11 and 12, these also being bent outwardly from the edges of the sections and being positioned diagonally with reference to the sections as best shown in Figs. 3, 5 and 6. The hinge flanges or lugs 20 and 21 are positioned for being received respectively in the upper and lower apertures 19 of the flanges 17 and 18. Each hinge lug is projected at its free end forming a hook-like structure so as to engage with the respective flanges 17 and 18 in interlocking relation to lock the two sections 11 and 12 together in operative positions as shown in Fig. 4. It will be noticed that each hinge lug 20 and 21 when in assembled position is substantially parallel to and in contacting relation respectively with the adjacent flanges 17 and 18 so as to provide a fulcrum for swinging the two sections together when closed upon the carton as best shown in Figs. 3, 5 and 6.

At the diagonally opposite corner of the supporting jig from the supporting hinge, a cam latch 22 is provided for locking and supporting the two sections 11 and 12 together when closed in supporting relation upon the carton as shown in Figs. 3 and 7. This cam latch includes an upper inclined cam plate 23 and a cooperating lower inclined cam plate 24. The cam plates 23 and 24 form projections of and are respectively supported by flanges 25 and 26 integral with the adjacent jig sections 11 and 12. Both of these flanges 25 and 26 are bent outwardly substantially into diagonal position with reference to the jig.

Since the improved filling supporting jig is rather large and bulky, especially for the three or four gallon or larger size cartons, it is desirable for storage purposes that the jig sections 11 and 12 be nested together as shown in Fig. 9 so as not to require so large a space for storage. For this purpose, the two sections 11 and 12 may be disconnected from each other by disengaging the connecting hinges and nested together as shown. The two sections are provided with handles 27 for use in engaging and disengaging the cam latch 22, being positioned adjacent thereto on the respective sections. For accommodating these handles when the two sections are nested together, each section is provided with an aperture 28 positioned for receiving the respective handles; each section is thus provided with an aperture 28 so that either section may be nested within the other section.

When it is desired to use the supporting jig 35 to support a carton during filling thereof, the two sections 11 and 12 are connected together by inserting the hinge lugs 20 and 21 into the respective receiving apertures 19 at the bases of the flanges 17 and 18. When the hinge lugs are thus 40 inserted, the two sections are moved longitudinally relative to each other so that the projected or hooked end portions of the hinge lugs are interengaged or interlocked with the apertures so that the two sections can be swung apart a short distance as shown in broken lines in Fig. 3. When the two sections are thus hinged together in interlocking relation, they are horizontally aligned with each other with the upper and lower edges of the entire supporting jig substantially 45 continuous. The empty carton may then be placed upon a flat supporting surface and the opened supporting jig placed therearound while resting on said supporting surface, whereupon the sections 11 and 12 are closed or swung together so as to contact with each of the four sides of the carton. During the final closing 50 swinging movement of the sections, the flanges 17 and 18 at the edges of the two sections 11 and 12 engage or fulcrum respectively with the hinge lugs 20 and 21 thus urging the two jig sections closely together at the hinged edges 55 thereof. The handles 27 may be used for this purpose. When in this closed position the jig rests upon the same flat surface which supports the carton which preferably extends slightly 60 above the upper edge of the jig so as to provide for placing a cover upon the carton after being filled.

Due to the interlocking engagement of the hinge 70 elements as above described, the two jig sections 11 and 12 are supported in horizontal alignment with each other, but they may be displaced longitudinally relatively to each other or longitudinally offset a short distance at their front or 75 cam latch edges so as to enable the inclined upper

and lower cam plates 23 and 24 to be engaged with each other, the handles 27 being used for this purpose. During this longitudinal displacement of the sections, the hinge connection and also the sections themselves are yieldingly stressed slightly so as to yieldingly urge them into their normal horizontally aligned position. Therefore, when the inclined cam plates 23 and 24 engage each other, the two sections are yieldingly urged together into their final closed position as shown in Fig. 1, and in full lines in Fig. 3. Hence in their final closed position the sections are constantly urged by this cam engagement against the walls of the carton. In this manner the carton is constrained at all times during the filling operation to maintain a constant measured volume, and all distortions and bulging of the carton walls are avoided. Due to the construction of the hinge at the hinged edge of the jig sections and to the cam latch, it will be noted that the adjacent inner surfaces of the supporting jig are smooth and unobstructed and all cavities or partially closed openings are avoided. Hence accumulations of dirt, moisture, bacteria, etc. are avoided, and the problem of keeping the supporting jig clean is simplified.

After the carton has been completely filled as indicated in Figs. 1 and 2, the cam latch 22 is released by again longitudinally displacing the sections 11 and 12 and swinging them apart and removing the jig from supporting position. Prior to removal of the supporting jig, the cover for the filled carton may be placed in position by telescoping the depending surrounding flanges thereof over the margin of the carton above the upper edges of the supporting jig.

In order to lower production costs, it is desirable that both sections 11 and 12 of the filling jig be made identical in structure. In the embodiment shown, this is accomplished by making the flange 25 of the section 11 identical in structure and position with the flange 26 of the section 12, and similarly making the diagonally opposite flange 17 of the section 12 identical in structure and position with the flange 18 of the section 11. When the two sections 11 and 12 are thus constructed, all that is necessary in assembling them is to reverse them end for end with reference to the other section whereupon they may be connected together in operative position as shown in the drawing and fully described above.

Since certain changes may be made in the above construction and different embodiments of the invention could be made without departing from the scope thereof, it is intended that all matter contained in the above description or shown in the accompanying drawing shall be interpreted as illustrative and not in a limiting sense.

The invention having thus been fully described, the following is claimed:

1. In a supporting filling jig for cartons, in combination, a pair of complementary wall sections, cooperating hinge means on adjacent edges of said respective wall sections, and latching means adapted to secure the remaining opposite edges of the wall sections together; said hinge means comprising a flange extending angularly outwardly of the confines of the jig from one of said first named adjacent edges and having a slot formed in the flange at the base thereof, said slot extending parallel with said wall edges, a flange extending angularly outwardly from the other of said first mentioned wall edges,

said last named flange having the form of a hook of but slightly smaller length than the length of the slot in the other flange, said hook flange received within said slot and the flange portion at the extreme end of said slot received within said hook, whereby the angular hook flange and the angular slotted flange are interlocked to form a hinge structure affording limited pivotal movement of the complementary wall sections of the jig.

2. The supporting filling jig as set forth in claim 1, in which two of the described hinge flange connections are provided along the first named adjacent edges of the wall sections, the second connection being the reverse of the first in that its slotted flange extends from the edge from which the first mentioned hook flange extends, and its hook flange extends from the edge from which the first named slotted flange extends, and the hooks face in opposite directions, thereby affording a stronger hinge and also enabling the wall sections to be of identical configuration whatever the side of the jig they occupy, thus facilitating construction.

3. In a supporting filling jig for cartons, in combination, a pair of complementary wall sections, cooperating hinge means on adjacent edges of said respective wall sections, and latching means adapted to secure the remaining opposite edges of the wall sections together; said hinge means comprising a flange extending angularly outwardly of the confines of the jig from one of said first named adjacent edges and having a slot formed in the flange at the base thereof and extending parallel with said wall edges, a flange extending angularly outwardly from the other of said first mentioned wall edges, said last named flange adapted to enter said slot and interlock with said first named flange to form a hinge structure, a second hinge connection of the type described provided along the first named adjacent edges of the wall sections, the second connection being the reverse of the first in that its slotted flange extends from the edge from which the first mentioned entering flange extends, and its entering flange extends from the edge from which the first mentioned slotted flange extends, thereby affording a stronger hinge and also enabling the wall sections to be of identical configuration whatever the side of the jig they occupy, thus facilitating construction.

4. The jig set forth in claim 3 in which said latching means comprises two cam-like projections extending from the respective adjacent wall edges of the second named or remaining pair, said projections being wedgingly interlocked to urge the wall sections to closed position about the hinges and into supporting and pressure contact with the carton.

5. In a supporting filling jig for cartons, in combination, a pair of complementary wall sections, cooperating hinge means on adjacent edges of said respective wall sections, and latching means adapted to secure the remaining opposite edges of the wall sections together; said latching means comprising an ear projecting angularly outwardly from each of the second named wall edges, and each ear having a projection bent toward the other and extending in the general direction of the said wall edges, said projections being positioned in opposition to each other when the wall sections are aligned with each other and being engageable by relative offsetting of said sections in the direction of extent of said edges,

the bent configuration of the ears causing the camming closure of the jig when they are interengaged.

6. In a supporting filling jig for cartons, in combination, a pair of complementary wall sections, cooperating hinge means on adjacent edges of said respective wall sections, and latching means adapted to secure the remaining opposite edges of the wall sections together; said hinge means comprising a flange extending angularly outwardly of the confines of the jig from one of said first named adjacent edges and having a slot formed in the flange at the base thereof and extending parallel with said wall edges, a flange extending angularly outwardly from the other wall edge of the first mentioned ones, said last named flange adapted to enter said slot and interlock with said first named flange to form a hinge structure, a second hinge connection of the type described provided along the first named adjacent edges of the wall sections, the second connection being the reverse of the first in that its slotted flange extends from the edge from which the first mentioned entering flange extends, and its entering flange extends from the edge from which the first mentioned slotted flange extends, said latching means comprising an ear projecting angularly outwardly from each of the second named wall edges, and each ear having a projection bent toward the other and extending in the general direction of the said wall edges, said projections being positioned in opposition to each other when the wall sections are aligned with each other and being engageable by relative offsetting of said sections in the direction of extent of said edges, the bent configuration of the ears causing the camming closure of the jig when they are interengaged, the reverse positions of the two hinge connections and the opposed extension of the latching ears enabling the wall sections to be of identical configuration, whatever the side of the jig they occupy, thus facilitating construction.

7. A polygonal supporting filling jig for cartons comprising, in combination, a pair of hinged side wall sections each including a plurality of the sides of the polygonal jig, hinge means connecting adjacent edges of the side wall sections at a corner at the junction of two sides; latching means connecting the remaining pair of side edges of the wall section; handle means projecting outwardly from the side wall sections, one upon either side of and adjacent to one of the pair of adjacent wall edges, and openings formed in the wall sections at corresponding points adjacent the other pair of adjacent edges for respectively receiving said handles when the two wall sections are disconnected and nested as for storage purposes.

8. In a supporting filling jig for cartons, in combination, a pair of complementary wall sections, cooperating hinge means on adjacent edges of said respective wall sections, and latching means adapted to secure the remaining opposite edges of the wall sections together; the hinge means comprising inter-engaging lugs projecting from the respective first named adjacent edges and shaped in reverse with respect to each other; the latching means also comprising interlocking projections extending from the respective second named adjacent wall edges and projected toward each other in exact reverse configuration, whereby said wall sections may be manufactured in identical form and connected in reverse upon assembly.
